UNITED STATES PATENT OFFICE.

HARTSON C. McCALL, OF WASHINGTON, DISTRICT OF COLUMBIA.

DESIGN FOR A BADGE OR SIMILAR ARTICLE OF MANUFACTURE.

Application filed August 8, 1924. Serial No. 10,403. Term of patent 14 years.

To all whom it may concern:

Be it known that I, HARTSON C. McCALL, a citizen of the United States of America, residing at Washington, District of Columbia, have invented a new, original, and ornamental Design for a Badge or Similar Article of Manufacture, of which the following is a specification, reference being had to the accompanying drawing, forming a part hereof.

Figure 1 is a plan view of a badge showing my new design. Fig. 2 is an edge view of the same.

As shown, the design consists in a blue

circle upon the vertical and horizontal diameters of which are red bands defining a cross and dividing a white field into quadrantal areas. Within the right angle of each of these quadrantal areas is a square outline in red and within each of these square outlines is a second square having its corners touching the sides of the first square at the centers thereof, all the squares being red.

I claim:

The ornamental design for a badge or similar article of manufacture, as shown and described.

HARTSON C. McCALL. [L.S.]
